ATTORNEYS

UNITED STATES PATENT OFFICE.

CARL FREDERICK KABISCH, OF NEW YORK, N. Y.

DESIGN FOR A BADGE OR SIMILAR ARTICLE.

SPECIFICATION forming part of Design No. 33,182, dated September 11, 1900.

Application filed August 10, 1900. Serial No. 26,531. Term of patent 3½ years.

To all whom it may concern:

Be it known that I, CARL FREDERICK KABISCH, a citizen of the United States, and a resident of the city of New York, borough of Manhattan, in the county and State of New York, have invented and produced a new and original Design for a Badge or Similar Article, of which the following is a specification, reference being had to the accompanying drawings, forming a part thereof, in which—

Figure 1 is an inner face view of a pin embodying the features of my design, and Fig. 2 is a vertical section through the pin.

The leading features of the design consist in the shell or the simulation of a shell and a pebble within the shell.

The minor features of the design consist in the corrugated form of the shell and in the

location of the pebble, which appears at the bottom central portion of the shell, and also in a beach scene which appears upon the inner face of the shell at the rear of the representation of the pebble.

Having thus described my invention, I claim as new and desire to secure by Letters Patent—

The design for a badge or similar article herein shown and described.

In testimony whereof I have signed my name to this specification in the presence of two subscribing witnesses.

CARL FREDERICK KABISCH.

Witnesses:

J. FRED. ACKER,
JNO. M. RITTER.
